HYDRAULIC MECHANISM

Walter H. Marsh, Crafton, Pa., assignor to Rockwell Manufacturing Company, Pittsburgh, Pa., a corporation of Pennsylvania

Application March 23, 1949, Serial No. 82,940

15 Claims. (Cl. 103—143)

1

This invention relates to hydraulic apparatus of the rotary type which may be used either as a motor or a pump and has for its general object and purpose to provide a simplified mechanism of this kind, the several parts of which may be quickly and accurately assembled within an outer casing for efficient and reliable operation.

It is a more particular object of the invention to provide an improved rotor with an improved mounting of rotor vanes therein, together with a cooperating division plate for pre-assembly with the rotor and insertion therewith between the inlet and outlet ports in the wall of a working chamber.

Another object of the invention is to provide a double-acting hydraulic pump or motor having division plates spaced 180 degrees apart between inlet and outlet ports in a liner sleeve, together with operating gearing for the rotor vanes and means for accurately timing the rotation of the vanes by said gearing relative to the rotor so that the vanes will safely pass over the division plates without interference.

It is a further object of the invention to provide a novel rotor and chamber ring construction which facilitates the accurate assembly of the vanes therein and permits the use of large size bearings of substantially equal diameter to the vane.

An additional object of the invention resides in the provision of an annular peripheral fluid receiving chamber in the rotor intersecting the vane openings together with a novel sectional ring and division plate assembly in said chamber slidably keyed to the liner sleeve for axial movement with the rotor, and having a face to face sealing relation to the opposite side walls of said chamber.

With the above and other objects in view, the invention comprises the improved hydraulic apparatus as above characterized and the construction and relative arrangement of the several parts, as will hereinafter be more fully described, illustrated in the accompanying drawings and subsequently incorporated in the subjoined claims.

In the drawings wherein I have disclosed one simple and practical embodiment of the invention and in which similar reference characters designate corresponding parts throughout the several views:

Figure 1 is a horizontal longitudinal section taken substantially on the line 1—1 of Figure 2 and showing a preferred assembly of my present improvements;

2

Figure 2 is a vertical transverse section taken substantially on the line 2—2 of Figure 1;

Figure 3 is a vertical longitudinal section of the outer casing taken substantially on the line 3—3 of Figure 2;

Figure 4 is a developed interior plan view of the casing;

Figure 5 is a vertical sectional view of the chamber ring and division plate assembly;

10 Figure 6 is an inner side elevation of one of the chamber ring sections;

Figure 7 is a transverse sectional view taken on the line 7—7 of Figure 5;

Figure 8 is a detail plan view of the division plate;

Figure 9 is a side elevation of one of the rotor vanes;

Figure 10 is an end view thereof on an enlarged scale.

20 Figure 11 is an outer side elevation of one rotor shaft bearing and housing assembly;

Figure 12 is a detail elevation of one of the end covers for the outer casing;

Figure 13 is an inner side elevation of the bearing housing and sun gear assembly;

Figure 14 is a vertical sectional view taken substantially on the line 14—14 of Figure 1;

Figure 15 is a side elevation of a modified form of rotor; and

Figure 16 is a section taken on line 16—16 of 30 Figure 15.

For purposes of illustration, in the present instance I have shown my improvements as applied to a hydraulic motor or pump of the double-acting type in which two intake and discharge phases occur in each revolution of the rotor. However, it will be understood that many of the novel features of the invention to be presently described are applicable as well to a pump or motor of the single-acting type.

40 Referring for the present more particularly to Figures 2, 3 and 4 of the drawings, the outer casing or housing structure 10 is of general cylindrical form and provided with inlet and outlet connections 12 and 14 respectively spaced 90 degrees apart. The cylindrical wall of the casing may be externally provided with spaced pairs of mounting lugs or ribs 16 and 18 respectively having tapped bores, which may be rigidly secured to a supporting base 20 by suitable bolts 22 with the inlet connection 12 or outlet connection 14 disposed either vertically or horizontally with relation to the casing body.

45 The casing 10 is internally formed with opposite end flanges 24 and an intermediate web or rib 26 which is circumferentially continuous and

55

comprises circumferential sections 28 thereof axially off-set in relatively opposite directions from the center line of the ports 12 and 14 and connected with each other by longitudinally extending sections 30 of the rib. The circumferential faces of the flanges 24 and ribs 26 are accurately finished for contact with the periphery of an insertable liner sleeve to be presently described. The rib 26 will thus form between the liner sleeve and the casing flanges 24 circumferentially continuous fluid inlet and outlet chambers 32 and 34 respectively which are in direct communication with the respective inlet and outlet ports 12 and 14.

The liner sleeve 36 which provides the working chamber and all stationary and movable parts associated therewith are first assembled externally of the casing 10 and then inserted as a unit to operative position therein. The liner sleeve 36 is of slightly less length than the casing 10 and is centrally provided with inlet ports 38 spaced apart 180 degrees and with outlet ports 40 also spaced apart 180 degrees and located in predetermined spaced relation from the respective inlet ports. When the liner sleeve is mounted in the casing, these ports 38 and 40 are in communication with the casing chambers 32 and 34 respectively at relatively opposite sides of two diametrically opposed sections 30 of the rib 26 which segregates the chambers 32 and 34 from each other.

To an intermediate section of the rotor shaft 42, the rotor 44 is non-rotatably connected by the key 46. Circumferential grooves 48 in the rotor shaft receive snap rings 50 to prevent axial displacement of the rotor relative to said shaft. The rotor 44 is formed with four cylindrical vane receiving openings 52 spaced apart 90 degrees which are on uniform diameter from end to end of the rotor. The rotor is further provided intermediate of its ends with an annular fluid receiving chamber 54 which intersects the openings 52.

As seen in Figure 9 of the drawings, each of the rotor vanes comprises a cylindrical body portion 56 which is cut away on one side intermediate of its ends to form a recess or pocket 58 having an arcuately concave bottom surface 60. The width of this vane pocket is substantially equal to the width of the annular chamber 54 in the rotor. The vane body 56 is provided at each end with a coaxial diametrically reduced cylindrical extension 62 and 64 respectively which journal the vane in ball bearings 66 of equal diameter to the vane body 56 mounted in opposite ends of the opening 52 in the rotor. The bearings are held against axial movement by the snap rings 68 positioned at the outer sides of the bearings in grooves formed in the wall of opening 52. The extension 64 at one end of the vane body 56 has a further cylindrical reduced axially projecting portion 70 which is formed with splines 72 one of which is accurately centered on the diameter which bisects the recess or pocket 58.

The splined portion 70 has a further reduced threaded terminal extension 74 to receive a retaining nut 76 for the vane driving gear or, pinion 78. This vane gear is internally splined to mate with the splines 72 and the gear teeth are formed so that one tooth is in radial alignment with a space between the internal splines so that the gear teeth will also be accurately positioned relative to the recess or pocket 58.

As shown in Figures 1 and 14 of the drawings between the vane gears 78 idler gears 80 are arranged. Each of these gears is fixed to a short

shaft 82 journalled at one end in a roller bearing 84 mounted in a recess in one end of the rotor 44. These shafts at their other ends are journalled in similar roller bearings 86 mounted in a cage member 88 which is rigidly secured to one end of the rotor 44 by suitable screws, indicated at 90 in Figure 14 of the drawing.

Referring now to Figures 5 to 8 of the drawings, a chamber ring and division plate assembly is arranged in a relatively stationary position within the annular chamber 54 of the rotor. In the present embodiment of the invention, the chamber ring consists of two substantially semi-circular sections 92 of equal diameter. Each of these ring sections is provided with openings 94 and 96 respectively which are adapted to register with respective inlet and outlet ports in the opposite sides of the liner sleeve 36. Each ring section is further provided with internal key-ways 98 extending from the openings 94 and 96 to the ends of the ring section. As shown in Figure 7 of the drawing, between each opening in the ring section and the adjacent end thereof, a counter-bored screw receiving opening 100 is provided in intersecting relation to the key-way 98. The large diameter section of this opening receives the head of an attaching screw 102 for a division plate 104, said screw head bearing upon the shoulders 106 formed by the small diameter section of the opening 100 at each side of the key-way 98.

Each division plate 104 is arcuately curved to provide inner and outer surfaces substantially concentric with the ring sections 92. The outer surface of the division plate is centrally formed with a longitudinally extending key rib 108 for engagement in the key-ways 98 of adjoining ends of the two ring sections 92, and at each end thereof, is provided with a tapped opening 110 to receive the threaded shanks of the attaching screws 102, the heads of which are received in recesses 112 in the key rib 108. Between the screw receiving openings 110 in the division plate, said plate is centrally provided with a key receiving slot 114, in which a flat metal key 116 has a driving fit and projects outwardly therefrom between the opposed ends of the ring sections 92 and in radially projecting relation to the outer circumference of said ring sections. As seen in Figure 2 of the drawings, these outwardly projecting portions of the two keys 116 are adapted to be fitted in diametrically opposite longitudinally extending internal key-ways 118 formed in the wall of the liner sleeve 36. Thus the chamber ring and the division plates will be non-rotatably held in position with respect to the liner 36. The outer edge faces of the chamber ring sections 92 form a running seal with the inner side walls of the rotor chamber 54 while the inner concave surfaces of the division plates 104 similarly form a running seal with the bottom of the fluid receiving chamber 54 of the rotor 44. The peripheral surfaces of the vanes 56 also have substantial fluid sealing contact with the inner surfaces of ring sections 92.

One end of the rotor shaft 42 is adapted to be journalled in a double roll ball bearing 120 mounted in a ring 122 having an external flange 124 for abutting contact against one end of the liner sleeve 36. A sun gear 126 is formed at one end of a sleeve 128 which loosely surrounds the rotor shaft 42. The other end of the sleeve 128 is provided with an outwardly extending annular flange 130 having a dowel pin 132 engaged in an opening 134 in the ring 122. The ring 122 and

the sleeve flange 130 are rigidly secured together by means of screws 136. It will be noted from reference to Figure 13 of the drawings that one of the teeth on the sun gear 126 is accurately centered on the same radius as the dowel pin 132.

The outer face of the ring 122 is recessed to receive the retainer ring 138 for the outer race of bearing 120 which is secured to said member by suitable screws 140 while a retainer nut 142 for the inner race of bearing 120 is threaded upon the reduced end of the rotor shaft 42.

As pointed out above, the splines 72 on vanes 56 are in predetermined position relative to the pockets 60, the teeth on the vane gears 78 are in predetermined position relative to the internal splines, and the teeth on the sun gear 126 are in predetermined position relative to the dowel pin opening 134. This results in simplicity of manufacture of each individual part but does result in a cumulative error in the positioning of the vanes 56 relative to the division plates 104 as the rotor is rotated. It has been found preferable to thus simplify the individual parts and to eliminate the accumulated error at one point rather than to position the teeth, splines and dowel hole on each part so that no error is introduced. The accumulated error introduced by alining the teeth, splines and dowel hole as described above will vary depending upon the size of the unit, the number of gear or spline teeth and other factors and in one embodiment of the invention amounts to approximately three degrees, forty-nine minutes in the angular position of the sun gear.

In order to eliminate this accumulated error, the ring 122 is provided with a tapped hole 143 which is out of radial alinement with the dowel hole 134 by the amount of the accumulated error, which, in the embodiment mentioned, would be three degrees, forty-nine minutes.

A screw 146 having an enlarged head which projects outwardly from the ring 122 is threaded into the tapped hole 143. For a purpose which will be later described, the ring 122 is also provided with four tapped holes 144 of the same size as the hole 143, two holes 144 being on each side of the hole 143. The holes 144 are the same distance from the center of the ring 122 as the hole 143 and the two holes 144 on each side of the hole 143 are spaced seventy-three degrees apart and seventy-three degrees from the hole 143.

A flanged cover 148 is provided for this end of the outer casing or housing. The cover flange has a plurality of equi-distantly spaced openings 150 to receive attaching screws 152 threaded into tapped bores 154 in the end of the casing wall. Preferably an annular gasket 156 of suitable material is interposed between the cover flange and the casing wall. The inner face of cover member 148 is provided, on the same diameter as the openings 143 and 144 in ring 122, with a plurality of recesses 158 which are circumferentially spaced apart 72 degrees, the purpose of which will be presently explained in connection with the final assembly of several parts relative to the outer casing or housing. Preferably, an annulus of suitable packing material, indicated at 160, is also interposed between the inner face of cover member 148 and the bearing retaining ring 138.

The rotor shaft 42 is also journaled in a double row ball bearing 162 mounted in a housing member 164 having an external flange 166 abutting the opposite end of liner sleeve 36. A spacing collar is interposed between the inner face of the bearing and the snap ring 50 on the rotor shaft as indicated at 168. The housing member 75

164 is provided with longitudinal key-ways 170 to mate with the ends of key-ways 118 in the sleeve 36 and receive the keys indicated at 172. Member 164 is further provided at diametrically opposite points with bores 174 to receive the locating dowels 176 carried by the end cover member 178 for the casing 16, between which and the attaching flange of the cover member an annular gasket 180 is interposed. The cover flange is provided with circumferentially spaced openings similar to those in cover member 148 to receive the attaching bolts 182 threaded into the tapped bores 184 in the end of casing 16.

As herein shown a flanged collar 186 is mounted in the cover member 178 and loosely surrounds the rotor shaft 42. It is held against rotation by the radial pin 188 on the cover engaged in a slot in one end of said collar. The collar 186 is surrounded by a fluid sealing ring 190 positioned in an annular groove formed in cover member 178. Between the flanged end of collar 186 and the inner race of bearing 162, a rotating mechanical face type shaft seal 192 is keyed to the shaft. Suitable seals are well known in the art.

At the opposite end of the casing 16, between two of the bolt receiving bores 154, a dowel pin 194 is secured therein. This pin is preferably located substantially mid-way between the inlet and outlet connections 12 and 14 of the casing and the projecting end thereof is adapted to be received in a cylindrical recess or bore 196 provided in the inner face of the attaching flange on cover member 148. As shown in Figure 12, one of the recesses 158 is in radial alinement with the dowel hole 196.

In assembling the above described parts, with respect to the outer casing or housing, the bearing 120 with ring 122 and sun gear 126 are first assembled on the end of the rotor shaft 42. After applying one of the stop rings 50 to shaft 42, the rotor 44 with case 88 and idler gears therein is then mounted on the shaft by means of key 46 and the other stop ring 50 applied to the shaft. The idler gears 80 are thus positioned in the radial plane of sun gear 126 and in mesh therewith.

The vanes 56 with their end bearings 66 are now inserted longitudinally into the openings 52 of the rotor. For the purpose of accurately establishing an initial position of the vane pocket 58 radially of the rotor axis, each vane is preferably provided on its cylindrical surface at diametrically opposite sides thereof with longitudinally extending score lines or gauge marks 200 which are circumferentially spaced a predetermined distance from the respective edges of the concave surface 60 of the vane. First two of the vanes are inserted into diametrically opposite openings 52 in the rotor with the gauge lines 200 on the vane in registration with the points of intersection of the circumferential base wall of chamber 54 with the opening 52 and with the pocket 58 in the vane facing inwardly towards the axis of the rotor. A 90° rotation is now imparted to the rotor whereby idler gears 80 in mesh with the relatively stationary sun gear 126 and vane gears 78 will rotate the two vanes 180° so that the pockets 58 thereof will open outwardly in the chamber 54. The other two vanes are then inserted with the gauge marks 200 thereon registering with the points of intersection of the other openings 52 in the rotor with the circumferential surface of chamber 54. It will of course be understood that

in the insertion of each vane to its applied position, the drive gear 78 therefor meshes with one of the idler gears 80.

The division plates 104 with keys 116 are now attached to relatively opposite ends of the respective chamber ring sections 92 by one screw 102 and said ring sections then inserted from opposite sides of the rotor into chamber 54 so that ends of the ring sections respectively opposing the ends of the ring section to which the division plates are attached will receive the key ribs 108 on the respective division plates and are then attached to said plates from the other screws 102. This rotor and division plate assembly is now inserted into the liner sleeve 36 from one end thereof, the projecting portions of the keys 116 being slidably fitted into the key-ways 118 of the sleeve wall. Thus, when the flange 124 on ring 122 abuts the end of sleeve 36 the rotor will be axially positioned with the division plates 104 located between the inlet and outlet ports 38 and 40 of the liner sleeve 36 and with openings 94 and 96 in the chamber ring sections in accurate registration with the respective ports in said sleeve. The peripheral surface of the ring 122 has a snug rotative fit within the end of the sleeve 36 for limited adjustment of said housing member and the sun gear 126 when cover member 148 is applied, as will be presently explained.

Spacing member 168 is now inserted over the rotor shaft, and bearing 162 and its housing member 164, then inserted into the other end of the liner sleeve 36 with keys 172 locking said housing member to the sleeve against relative rotation. The rotating shaft seal member 192 is then inserted over end of shaft. When the cover member 178 is now applied and its dowels 176 engaged in the bores 174 and secured to the end of the casing by bolts 182, the sleeve and bearing housing are rigidly held against rotative displacement relative to the casing.

The other end cover 148 for the casing is finally applied. The projecting end of dowel pin 194 is received in the bore 196 of the cover member while the head of screw of 146 is received in a recess 158 in said cover member. Thus as the cover member 148 is moved to its final position in which the dowel pin 194 will enter the dowel hole 196, a slight rotative movement will be imparted to the ring 122 and sun gear 126 rotated through the same angle as the angle between dowel hole 134 and tapped hole 143 in ring 122.

Assembly of the cover 148 with the screw 146 in tapped hole 143 properly positions the vanes 56 if all of the parts are wholly accurate. If however there are mechanical inaccuracies which affect timing so that the vanes 56 do not properly clear the division plates 104 these inaccuracies can be compensated by removing the screw 146 from the hole 143 and placing it in one of the holes 144 where it will engage with a corresponding recess 158 in the cover 148. As pointed out above, the holes 144 are spaced seventy three degrees apart while the recesses 158 are only seventy two degrees apart so that the four holes 144 permit two degrees of adjustment of the angular position of ring 122 and sun gear 126 in each direction. If the sun gear 126 has twice as many teeth as the vane gears 78, a two degree change in the angular position of the sun gear 126 causes a four degree change in the angular position of the vanes 56 relative to

the rotor. It will of course be understood that screw 146 functions as a key to restrain ring 122 against any further rotative movement relative to the liner sleeve from its adjusted position and to retain the sun gear 126 in a stationary or fixed position relative to the rotor shaft.

From the above description, it will be seen that unlike prior apparatus of this kind, the division plates are not secured in fixed position relative to the working chamber but are slidably keyed to the liner sleeve 36. Thus, in the event of any slight axial play of the rotor shaft or axial displacement of the rotor relative to the shaft, the chamber ring sections and the attached division plates 104 will move axially as a unit therewith. In this manner, high frictional wear and excessive resistance to rotation of the rotor is avoided and precise axial positioning of the rotor with respect to the division plates in assembling is rendered unnecessary.

The construction of the rotor and chamber ring by which the chamber ring extends into the chamber formed in the rotor is an important feature of the invention since it results in face sealing between the rotor and chamber ring rather than edge sealing and also permits the use of larger vane bearings. This simplifies and facilitates both manufacture and assembly of the apparatus.

While I prefer to make the rotor 44 of one piece and to make the chamber ring 92 of two pieces so that the chamber ring can be mounted in the chamber 54, it is possible to make the rotor of two pieces as shown in Figures 15 and 16. The chamber ring 92 may then be made as shown in Figures 5, 6 and 7 but need not be separated for assembly or may be made of a single piece.

The rotor shown in Figures 15 and 16 comprises a body 210 having a central bore 211 for receiving the shaft 42. The body 210 has a reduced portion 213 and a flat wall portion 214 extending radially from one end of the reduced portion 213. A flat plate 215 is secured to the body 210 at the other end of the reduced portion 213 by screws or bolts 216. The wall portion 214, reduced portion 213 and plate 215 form an annular fluid chamber identical in form with the fluid chamber 54.

While the plate 215 is secured to the rotor body 210, the vane openings 217 and a keyway 218 are formed in the rotor body and plate assembly. The plate 215 may then be removed and the chamber ring and division plate assembly shown in Figure 5 may be placed in position without being disassembled. The plate 215 is secured to the rotor body 210 and the keyway 218 assures accurate alignment of the vane openings in the plate and rotor body.

The liner sleeve 36 is maintained in a fixed axial position between the end cover members 148 and 178 for the outer casing while the dowels 176 serve to accurately position the liner sleeve with its inlet and outlet ports 38 and 40 respectively located at relatively opposite sides of the longitudinally extending portions 30 of the separating rib 26 between the inlet and outlet chambers 32 and 34 respectively of the casing 10. Thus, it will be understood, from reference to Figure 2 of the drawings that in each revolution of the rotor 44, each of the rotating vanes 56 operates to twice transfer liquid in predetermined volume from the inlet chamber 32 of the casing 10 to the outlet chamber 34 thereof. However, it will be understood of course that the essential features of my present improvements may be also applied to a

single acting type of hydraulic apparatus, in which the use of only one division plate is required.

It will be appreciated that the present invention provides an hydraulic apparatus of this kind involving a minimum number of mechanical parts of simple structural form which may be expeditiously and accurately assembled for maximum operating efficiency without necessitating special knowledge or unusual manual dexterity. While the mechanical principles of the invention are illustrated by a selected embodiment thereof, in the construction of apparatus of a required capacity designed for a particular use, it may be found desirable to substitute parts of somewhat different structural form but having equivalent functional characteristics of corresponding parts of the apparatus herein described.

The invention may be embodied in other specific forms without departing from the spirit or essential characteristics thereof. The present embodiment is therefore to be considered in all respects as illustrative and not restrictive, the scope of the invention being indicated by the appended claims rather than by the foregoing description, and all changes which come within the meaning and range of equivalency of the claims are therefore intended to be embraced therein.

What is claimed and desired to be secured by United States Letter Patent is:

1. In hydraulic apparatus of the rotary type having a cylindrical wall forming a working chamber and circumferentially spaced inlet and outlet ports, a rotor mounted in said chamber having an annular peripheral chamber in fluid communication with said inlet and outlet ports and a plurality of circumferentially spaced cylindrical openings extending longitudinally through the rotor in intersecting relation to said annular chamber, a relatively stationary division plate in said annular chamber between said ports, a sealing chamber ring fixed to said division plate between opposite side walls of said annular rotor chamber and in running contact with the inner faces thereof, said chamber ring having spaced openings therein registering with said inlet and outlet ports respectively, a vane rotatably mounted in each of said openings, and means for operating said vanes in timed relation to the rotation of the rotor comprising a sun gear, means mounting said gear in fixed co-axial position in the working chamber relative to said rotor, a housing fixed to one end of the rotor, a plurality of idler gears in mesh with said sun gear each having a shaft journaled at opposite ends in said housing and rotor respectively, and a gear fixed to one end of each vane within said housing in meshed engagement with one of said idler gears.

2. Hydraulic apparatus as defined in claim 1, together with additional means for rotatably adjusting the sun gear to initially establish a predetermined position of the vanes in the rotor for uninterrupted movement with and relative to the rotor over said division plate.

3. In hydraulic apparatus of the rotary type, a casing having fluid inlet and outlet connections, rotary mechanism mounted within said casing including a rotor having an annular peripheral chamber in fluid communication with said inlet and outlet connections and a plurality of vanes rotatably mounted in the rotor in intersecting relation with said chamber, a relatively stationary division plate in the rotor chamber between said inlet and outlet connections, and means for timing the rotation of said vanes rela-

tive to rotation of the rotor for non-interfering movement of the vanes over the division plate, comprising gearing operatively connected with the vanes and including a relatively stationary sun gear in co-axial relation with the rotor, an end cover for said casing, a member having a fixed connection with said sun gear, and said cover having means co-acting with said member in movement of the cover to applied position relative to the casing to rotatably adjust the position of the sun gear and initially establish a predetermined position of the vanes in the rotor.

4. Hydraulic apparatus as defined in claim 3, wherein a recess is provided in said end cover and a dowel pin is fixed to the end of the casing and engaged in said recess to support and direct the cover to its applied position.

5. Hydraulic apparatus as defined in claim 3, together with a ring, a bearing mounted in said ring, a supporting shaft for the rotor journaled at one end in said bearing and means rigidly connecting said sun gear to said ring, and wherein said member is carried by said ring and coacts with the means on the cover to retain said sun gear and ring in a stationary position.

6. Hydraulic apparatus as defined in claim 5, in which said connecting means comprises an end flange on said sun gear and a dowel pin connecting said end flange to said ring and located in radially centered relation to a tooth on said sun gear, and wherein said ring is provided with a plurality of circumferentially spaced openings, said member being engaged in one of said openings adjacent to the dowel pin but out of radial alignment therewith) and the co-acting means on said cover comprises a plurality of recesses therein in different circumferentially spaced relation from the openings in said ring for selective engagement with said member.

7. In hydraulic apparatus of the rotary type, an outer casing provided with inlet and outlet connections, a unitary assembly axially insertable within said casing comprising a liner sleeve for the casing having circumferentially spaced inlet and outlet ports and an axial keyway extending between said ports, a shaft having a rotor fixed thereto provided with an annular peripheral chamber and a plurality of vanes mounted in said rotor and movable relative thereto, and a division plate in said rotor chamber provided with a key slidable in said keyway in the axial insertion of the shaft and rotor within said liner sleeve to position said division plate between the inlet and outlet ports in non-rotatable relation to the rotor and said liner sleeve.

8. Hydraulic apparatus as defined in claim 7, wherein said assembly further comprises bearing supporting housings for the rotor shaft closing the opposite ends of said liner sleeve.

9. Hydraulic apparatus as defined in claim 8, together with operating means for the rotor vanes including a stationary member fixed to one of said bearing housings.

10. Hydraulic apparatus as defined in claim 7, wherein said assembly further comprises a bearing supporting housing for the rotor shaft fixed at one end to the liner sleeve, and an end cover member for the outer casing having means to co-act with means on said housing and non-rotatably position the liner sleeve in said casing with said inlet and outlet ports thereof in fluid communication with the inlet and outlet connections respectively of said casing.

11. In hydraulic apparatus of the rotary type, a casing having an inlet port and an outlet port spaced from said inlet port a rotor having a cen-

tral hub portion and end plates extending outwardly from said hub portion to form an annular chamber, a chamber ring comprising two semi-circular ring sections disposed between said end plates and in running contact therewith, said chamber ring having an inlet port and an outlet port spaced apart the same distance as the ports in said casing, a division plate connecting said semi-circular ring sections between said inlet port and said outlet port, means for positioning the chamber ring relative to the casing with the inlet openings and the outlet openings of the casing and chamber ring in alinement, and vanes rotatably mounted in said rotor within the annular chamber and means for rotating said vanes.

12. In a hydraulic mechanism of the rotary type, a rotor having an annular recess forming the bottom and sides of a fluid chamber, a chamber ring comprising a pair of semi-circular ring sections extending into said recess in running sealing relationship with the sides of said fluid chamber, a division plate connecting said semi-circular ring sections and extending into said fluid chamber, said chamber ring having a fluid inlet port on one side of said division plate and a fluid outlet port on the other side of said division plate, and a plurality of vanes rotatably mounted in said rotor and extending across said chamber.

13. In hydraulic mechanism of the rotary type, a housing having fluid inlet and fluid outlet means, a shaft rotatably mounted in said housing, a rotor fixed on said shaft, said rotor having an annular peripheral fluid chamber therein, a plurality of vanes rotatably mounted in said rotor parallel to said shaft and extending across said chamber, a chamber ring extending into said chamber, a division plate secured to said chamber ring within said chamber, said chamber ring having a fluid inlet opening on one side of said division plate and a fluid outlet opening on the other side of said division plate, means for axially slidably securing said chamber ring in said housing, means connecting the fluid inlet means of said housing with the fluid inlet opening of the chamber ring and means connecting the fluid outlet means of said housing with the fluid outlet opening of said chamber ring.

14. In hydraulic apparatus of the rotary type having a cylindrical wall forming a working chamber and provided with circumferentially spaced inlet and outlet ports; a rotor mounted in said working chamber having an annular peripheral chamber in fluid communication with said ports; vanes movably mounted in said rotor to traverse said annular rotor chamber; a division plate in said annular rotor chamber; a pair of semi-circular sealing chamber ring sections fixed to said division plate between the opposite side walls of said annular rotor chamber

and in running contact with the inner faces thereof, said chamber ring sections having spaced openings therein registering with said inlet and outlet ports respectively; and means non-rotatably connecting said division plate to the wall of said working chamber between the inlet and outlet ports for movement with said rotor axially of the working chamber.

15. In hydraulic apparatus of the double acting rotary type; a cylinder providing a working chamber with circumferentially spaced inlet and outlet ports in opposite sides of the cylinder wall; a rotor mounted in said chamber having an annular peripheral chamber in fluid communication with said ports and a plurality of relatively movable vanes mounted in said rotor to traverse said annular chamber; a pair of division plates adapted to be assembled in the annular rotor chamber at diametrically opposite sides of the rotor, said plates each having means slidably co-acting with means internally formed on the cylinder wall in the axial movement of the rotor to operative position within the cylinder to retain said division plates against circumferential displacement relative to the cylinder wall and rotor while permitting axial unitary movement of said plates with the rotor in the operative position of the rotor; and a pair of stationary ring sections in the rotor chamber each fixed at its opposite ends to the respective division plates and having openings therein registering with said inlet and outlet ports at opposite sides of the cylinder, said ring sections having running seal contact with opposite side walls of the rotor chamber and the rotor vanes.
